DIRECTLY HEATED ALTERNATING CURRENT CATHODE RADIO TUBE

Application filed August 3, 1927. Serial No. 210,262.

Our invention relates to electron discharge tubes and particularly to such tubes designed for use as amplifier and receivers in radio circuits.

5 One of the objects of our invention is to produce a tube for radio receiving and amplifying purposes, the cathode of which may be heated by alternating current of the frequency commonly supplied for house lighting without producing an objectionable hum in telephone receivers or loud speakers supplied thereby.

10 Another object of our invention is to produce a form of cathode adapted for radio tubes of the kind above described which may be heated by alternating current of commercial frequency without the production of any objectionable hum in apparatus connected thereto.

15 20 A further object of our invention is to devise a way to proportion a cathode of a filamentary type to be used in radio tubes of the kind described above in such a way that it may be heated by alternating current of audible frequency without the production of objectionable hum in the apparatus connected thereto.

25 30 Other objects of our invention will be apparent through reading the following specification taken in connection with the accompanying drawing, in which

Figure 1 shows a radio tube embodying our invention.

35 Fig. 2 is a diagram which will be used to explain the properties thereof.

The ordinary radio receiving or amplifying tube of the prior art comprises a cylindrical anode, a grid electrode surrounded thereby and, near the center of the cylinder, a cathode comprising a filament adapted to be heated to a temperature sufficiently high to emit electrons freely. The ordinary way of heating this filament has been to supply it with current from a battery or other direct-current source.

40 Considered as sources of electric power, batteries are relatively expensive devices and it would have been desirable at all times to have heated the filament by current from ordinary house lighting mains. However, a

very large proportion of house lighting services are of the alternating current type and when it was attempted to use such sources of supply for the filament, an objectionable hum of a harmonic frequency of the alternating current was produced in instruments such as telephones or loud speakers connected in the plate circuits of the radio tubes.

55 60 It has been the object of the experiments which we have carried out to discover the cause of this hum and to devise ways by which it might be eliminated.

65 As the result of the analysis which we have made of this subject we have found that a number of separate causes contribute in greater or less degree to the production of this objectionable phenomenon. We have found that sources which have given rise to this trouble are:

70 1. The attraction of electrons emitted from the negative end of the filament by the end of the filament which is positive at any particular instant.

75 2. The effect of potential drop along the filament which rises and falls in the course of the alternating current cycle and which, as we will hereinafter show produces fluctuations in the current from the anode.

80 3. The alternating magnetic field set up by the alternating current through the filament, which field deflects the electrons from the straight path which they would otherwise follow between the cathode and the anode.

85 4. The variations in temperature of the filament, resulting from the rise and fall of the alternating heating current in its cycle.

90 95 In receiving tubes of the many types, one or more of these causes may produce effects in the anode circuit so small as not to be of practical importance. It is probably only the two effects first mentioned which produce the hum actually heard in the case of ordinary receiving tubes. We have discovered that the instantaneous effects of the first and third factors listed are opposite in kind to those produced by the second, so that the latter tends to increase the anode current at the time each of the former tends to de- 100

crease it. The effect of the fourth, while a periodic quantity of the same frequency as the first and third, is probably dephased therefrom by nearly three quarters of a cycle so it cannot be exactly neutralized by either of the first three. Except for very thin filaments it is negligible in magnitude however.

We have further found that by properly proportioning the diameter, length, shape, resistivity, and temperature of operation of the filament, it is possible to make the first two effects substantially equal as well as opposite to each other, from which it follows that the net effect of all is made zero.

15 While it is possible to embody the broad principles of our discovery, in many different structures, we show herewith a tube which makes use of them in a cathode which is similar to certain cathodes of prior art except in 20 respect to this proper proportioning between its various dimensions.

15 Referring in detail to Fig. 1 which illustrates an embodiment of our invention, an evacuated container 1 of the conventional type has a press 2 upon which the in-leading wires support a cylindrical anode 3, a grid 4 and a cathode filament 5 which specifically embodies the features of our invention as above outlined. The anode 3 and grid 4 are 30 of conventional type and need no separate description. The cathode consists of a V-shaped filament having a length of approximately 5.1 cms. and the ends of the V being approximately 1.0 cms. apart. This filament 35 comprises a base of nickel approximately .0056 x .0325 mms. upon which is deposited a coating comprising a mixture of barium oxide and strontium oxide, approximately 0.002 mms. thick. Cathodes coated in this 40 way are well known in the art under the term oxide coated cathodes. Except for its relative proportions therefore a tube of our invention resembles closely those known to the prior art.

45 The resistance when hot, of this cathode is about 1.4 ohms and it operates with about 1.5 volts impressed across its terminals.

The cathode is positioned in the middle 50 plane of the anode and is spaced from it by approximately 2.2 mm.. The grid may be positioned about midway between cathode and anode. Such a tube is designed to operate with a 135 volt B-battery between cathode and anode.

55 Turning to the various causes of hum enumerated above, their effects may be analyzed in connection with the diagram of Fig. 2, which may be considered as a view looking down on the anode and cathode 60 shown in Fig. 1. The mid-point of the cathode is taken as the axis of coordinates, and distances to the right of the point are represented by the quantity +X while distances to the left thereof, are represented by 65 -X. The two ends of the filament are locat-

ed at the distance +L and -L respectively. Between the mid-point of the cathode and the plate, the B-Battery, having constant electromotive force e_p , is connected. Between the two ends of the cathode is impressed the electromotive force $e = E \sin pt$. Considering the first cause of hum listed above, there will exist at the surface of the cathode filament, an electric force due to the voltage between opposite ends of the filament. This force will be uniform all along the filament due to the fact that both the distance and the potential difference between points opposite each other on the two sides of the V decrease at the same rate as the apex of the V is approached. This force may as a first approximation be considered to side-track certain electrons emitted from the cathode which otherwise would flow to the anode. Because the voltage drop along the filament is small compared with that between the anode and cathode, the number of electrons thus side-tracked is relatively small.

The best known formulae for electron flow shows it to be approximately proportional to the square of the mean electric force between anode and cathode. Since we are here dealing with only a small correction term, the numbers of electrons side-tracked may thus be considered to be proportional to

$$\frac{(E \sin pt)^2}{2L}.$$

Of the total number of electrons emitted per second by the filament a certain number N_0 would reach the anode if not side-tracked as aforesaid. The number which will be left available for flow to the anode when the voltage $E \sin pt$ is impressed on the cathode may be expressed as

$$N = N_0 \left(1 - \frac{KE^2 \sin^2 pt}{4L^2} \right)$$

Where $E \sin pt$ is IR drop between ends of the cathode $2L$ is the distance separating the ends of the cathode filament and K is a constant.

Turning to the second cause of hum, the current flowing to the anode from the cathode may be calculated with the aid of Fig. 2 115 by the use of the well known Langmuir formula.

$$i_p = Nl e^t$$

Where i_p is current from a hot filament of length l to a radio tube anode, e is the potential difference between the cathode and the anode and N is proportional to the number of electrons available at the cathode.

In the case of a three-electrode tube the 125 Langmuir formula takes the form

$$i_p = Nl (E_p + \mu E_g)^t$$

where E_p is anode voltage; E_g is grid voltage; and μ is the amplification constant of 130

the tube; see page 417 of "Principles of Radio Communication" by J. H. Morecroft 1921, Wylie and Sons, New York, publishers.

Applying the foregoing formula to current between filament and anode in Fig. 2, the potential difference between the anode and any point on the cathode at a distance x from the mid-point thereof is represented by

$$10 \quad e = e_p + \frac{x}{2L} E \sin pt$$

In accordance with the Langmuir formula, the current flowing to the plate from a small element dx will be represented by

$$15 \quad dip = N \left\{ e_p + \frac{x}{2L} E \sin pt \right\} dx$$

In ordinary receiving tubes, the filament voltage E is small compared to e_p . Hence, this expression may be expanded and written

$$20 \quad dip = Ne_p^2 \left\{ 1 + \frac{3x}{4L} \frac{E}{e_p} \sin pt + \frac{3}{32} \frac{x^2 E^2}{L^2 e_p^2} \sin^2 pt \right\} dx$$

25 Substituting for Ne value as given above and dropping the terms of powers higher than the second of

$$\frac{E}{e_p}$$

30 gives

$$dip = N_o e_p^2 \left\{ 1 + \frac{3x}{4L} \frac{E}{e_p} \sin pt + \left(\frac{3}{32} \frac{x^2 E^2}{L^2 e_p^2} - \frac{KE^2}{4L^2} \right) \sin^2 pt \right\} dx$$

35 Upon integration, this gives for the total anode current

$$40 \quad i_p = N_o e_p^2 \left\{ 2L + \left(\frac{L}{32} \frac{E^2}{e_p^2} - \frac{KE^2}{4L} \right) (1 - \cos^2 pt) \right\}$$

This shows that the anode current consists of direct current component

$$45 \quad N_o e_p^2 \left\{ 2L + \frac{L}{32} \frac{E^2}{e_p^2} - \frac{KE^2}{4L} \right\}$$

and an alternating current component

$$50 \quad N_o e_p^2 \left\{ \frac{L}{32} \frac{E^2}{e_p^2} - \frac{KE^2}{4L} \right\} \cos 2pt$$

55 which is of double frequency. It will be noticed that this alternating component has the character of an increment of the direct current which would flow if the B-battery alone were supplying power to the circuit.

If

$$\left(\frac{L}{32} \frac{E^2}{e_p^2} - \frac{KE^2}{4L} \right)$$

60 is zero the alternating current component producing hum disappears.

Accordingly, we have conceived that it is possible to build a tube so proportioned that the quantity in parenthesis shall be zero and that no hum will be produced in such a tube.

65 For instance by varying L , the distance sepa-

rating the ends of the V-shaped filament, the hum due to the factors above-enumerated may be reduced to zero. The equation in the paragraph above reduces to

$$70 \quad e_p = \frac{L}{\sqrt{8K}}$$

It will be evident that a variation of L is not the only way of eliminating hum by making the quantity in the parenthesis zero. Thus, since the ratio of E to e_p is not the same in the two terms, a variation of this ratio may be used to make the two terms equal. Thus, by varying the ratio of B-battery voltage to filament voltage, the desired adjustment can be attained.

In most cases, the third factor enumerated as cause of hum is of negligible effect; but in any case, where its effects are appreciable, it is possible to counteract them, also by increasing or decreasing the second term in the parenthesis, as by varying L . That is to say L should be decreased to counteract hum if the magnetic field is appreciable.

It will also be evident that where the third cause of hum enumerated is not negligible, to increase or decrease its value by changing the magnitude of the cathode heating current is a possible way to cause the opposing factors in hum to balance. Likewise by changing the specific resistivity of the filament material the voltage and current in the cathode may be varied, and the magnitude of the terms, entering into the foregoing equations thereby varied. Once they have become acquainted with the foregoing method of analyzing the factors entering into hum productions numerous other specific ways of varying the quantities to balance the terms will be evident to those skilled in the art.

The final object to be attained by any of the foregoing methods is, of course, that the effects of the various causes shall sum up to zero. Our invention broadly covers the elimination of hum by such an adjustment of the various factors which cause it.

While, in compliance with the patent statutes, we have described one embodiment of our invention in detail, and have disclosed our understanding of the principles underlying it, our invention is not dependent upon the correctness of the assumptions underlying the mathematical analysis here given, and we do not wish to be limited thereby, since its purpose was mainly to illustrate the relations of various quantities and the method of using them in proportioning a structure embodying our invention. It will be evident to those skilled in the art that the broad principles which we have utilized may be applied in connection with different specified embodiments, and we therefore, desire that our claims shall be limited only by their explicit terms and in accordance with the prior art.

We claim as our invention:

1. In combination with an anode, a cathode adapted to emit electrons, a source of direct current connected in circuit therewith, a source of alternating current connected to heat said cathode, said cathode heating current being large enough so that the magnetic flux produced by it in the neighborhood of the filament has a substantial tendency to produce variations in the anode current, said cathode being so proportioned that the fluctuations produced by the alternating potential drop along the cathode in the anode current are substantially equal to the fluctuations in said anode current due to cross flow of electrons between the different parts of the cathode and due to the alternating magnetic field set up by the alternating current through the cathode.
2. The method of operating an electron-discharge tube having a V-shaped filament energized by alternating current and an anode connected through a direct current source to said V-shaped filament, said alternating current being large enough so that the magnetic flux produced by it in the neighborhood of the filament has a substantial tendency to produce variations in the anode current, which comprises spreading the legs of said V-shaped filament and spacing said filament from said anode that the effect on the anode current because of the cross flow of electrons between portions of the filament and because of the alternating magnetic field set up by the alternating current through the filament is neutralized by the effect on the anode current of the rise and fall of potential of various portions of the filament with alternations of the current therethrough.
3. In testimony whereof, we have hereunto subscribed our names this 26th day of July, 1927.

WILLIAM J. KIMMELL.
LEE SUTHERLIN.
